UNITED STATES PATENT OFFICE.

AMES N. McQUERN, OF CANTON, OHIO, ASSIGNOR OF ONE-HALF TO JACOB E. FRAILEY,
OF CANTON, OHIO.

FACING-BRICK.

938,430.

Specification of Letters Patent. Patented Oct. 26, 1909.

Application filed February 25, 1909. Serial No. 480,080.

To all whom it may concern:

Be it known that I, JAMES N. McQUERN, a citizen of the United States, residing at Canton, in the county of Stark and State of Ohio, have invented certain new and useful Improvements in Facing-Brick; and I do hereby declare that the following is a full, clear, and exact description of the same, reference being had to the accompanying drawing, making a part of this specification, and to the numerals of reference marked thereon, in which—

Figure 1 is a view showing a number of tile placed in proper relative position. Fig. 15 2 is a detached perspective view of a single tile looking at the back of the tile. Fig. 3 is a transverse section showing two tile placed in proper relative position and secured to the sheeting also showing a portion 20 of the third tile.

The present invention has relation to facing brick especially designed to take the place of ordinary and common brick used for the purpose of veneering buildings.

Similar numerals of reference indicate corresponding parts in all the figures of the drawing.

In the accompanying drawing, 1 represents the ordinary sheeting that is secured to the building in the usual manner and to which sheeting the facing brick is connected as hereinafter described. The facing brick 2 is formed of any convenient size and of clay properly burned to produce a tile suitable for the purpose designed. The facing brick 2 is provided with the lapping flanges 3 and 4, which flanges are located substantially as shown in Fig. 2 and as shown they are so located that two or more tile can be brought into the same vertical or horizontal plane.

For the purpose of producing water tight joints the contact faces of the flanges 4 and 3 are provided with grooves 5 and ribs 6 and the ribs 6 seated in the grooves 5 as illustrated in the drawing. Each tile is provided with apertures 7, through which apertures nails 8 or their equivalents are passed and for the purpose of allowing the lapped flanges to abut snugly against each other the apertures 7 are provided and are counter-

sunk as illustrated in Figs. 1 and 3 so that the heads of the nails 8 will not extend beyond the faces of the flanges. The flanges are provided with the horizontal and vertical grooves 5 and ribs 6 so that the vertical joints and the horizontal joints will be protected as against the entrance of moisture.

For the purpose of providing a means for giving a pleasing appearance, the ends and edges of each facing brick 2 are beveled, but I do not desire to be limited to this construction as the only object is to give a more pleasing and artistic effect to a finished wall.

While it is not my desire to be limited to the various uses to which the facing brick can be used yet the tile herein described is more specifically designed to be used in the construction of the vertical walls of buildings.

It will be understood that in the construction of walls, tiles of different lengths should be produced so that the vertical joints in the horizontal tiers can be broken or brought out of alinement as illustrated in Fig. 1.

In order to bring the outer faces of the facing brick when placed in the position shown in Fig. 1 all in the same plane, the thickness of the extended or lapped flanges should be one-half the thickness of the body of the tile so that the front faces and the rear faces of the tile are all brought into the same planes.

Having fully described my invention what I claim as new and desire to secure by Letters Patent, is—

An improved article of manufacture, a facing brick of the class described, consisting of a body portion, side and end overlapping flanges formed of a thickness substantially one-half the thickness of the body portion said flanges provided with ribs and grooves respectively and the ribs adapted to be seated in the grooves of adjacent bricks, substantially as and for the purpose specified.

In testimony that I claim the above, I have hereunto subscribed my name in the presence of two witnesses.

JAMES N. McQUERN.
